DESIGN FOR A COMBINED TRIGGER GUARD AND FINGER GRIP FOR FIREARMS

Iver O. Mossberg, West Haven, Conn., assignor to O. F. Mossberg & Sons, Inc., New Haven, Conn., a corporation of Connecticut

Application December 27, 1937, Serial No. 73,888

Term of patent 7 years

To all whom it may concern:

Be it known that I, Iver O. Mossberg, a citizen of the United States, residing in West Haven, in the county of New Haven and State of Connecticut, have invented a new, original, and ornamental Design for a Combined Trigger Guard and Finger Grip for Firearms, of which the following is a specification when taken in connection with the accompanying drawing, in which

Figure 1 is a side elevational view of a combined trigger guard and finger grip for firearms showing my new design and,

I claim:

The ornamental design for a combined trigger guard and finger grip for firearms, substantially as shown.

IVER O. MOSSBERG.
